UNITED STATES PATENT OFFICE.

HARY H. HUDSON, OF FLINT, MICHIGAN.

REVERSING-GEAR.

SPECIFICATION forming part of Letters Patent No. 314,380, dated March 24, 1885.

Application filed January 16, 1884. (No mode'.)

To all whom it may concern:

Be it known that I, HARY H. HUDSON, of Flint, in the county of Genesee and State of Michigan, have invented new and useful Improvements in Reversing-Gear; and I do hereby declare that the following is a full, clear, and exact description thereof, reference being had to the accompanying drawings, which form a part of this specification.

This invention relates to an improvement in reversing-gear for steam-engines; and the invention consists in the construction, arrangement, and combination of devices by means of which the crank which operates the valve or valves is stopped in its movement long enough to change the time of action of the valve so as to produce a reversing of the motion of the engine-crank.

In the drawings which accompany this specification, Figure 1 is a plan view of a steam-engine to which my reversing-gear is applied. Fig. 2 is a detached perspective view of the reversing-gear. Fig. 3 is a side elevation of the same with the valve-rod removed. Fig. 4 is a cross-section on the line xx in Fig. 3. Fig. 5 is a similar cross-section on the line yy in Fig. 3. Fig. 6 is a section on line zz , in a plane at right angles to the sections in Figs. 4 and 5. Fig. 7 is a detached view of the loose ring. Fig. 8 is a detached perspective view of the dog.

In Fig. 1 my reversing-gear is shown applied to a steam-engine of ordinary construction, wherein A is the cylinder, B the steam-chest inclosing an oscillating valve, C the piston, D the crank-shaft, E the fly-wheel, and F the valve-rod. The valve-rod F is operated by a crank-wheel, which consists of two concentric parts, G G', one within the other. The inner part or hub, G, is fast upon the shaft, and the outer part, G', which carries a wrist-pin, I, forms a loose ring around it, which is slipped over the hub G, and is held in position thereon by the flange a of the hub G and the washers bb , secured to it upon the opposite side. The fast portion of the crank-wheel contains a dog, J, which is loosely inserted into a radial socket, c , at the bottom of which is placed a coil-spring, d . The dog J is provided with a wedge-shaped head, e , which is adapted to engage into either of the two similar-shaped re-

cesses $f f'$ upon the inner face of the loose ring G'.

K is a stop, which is secured to the fast portion G of the crank-wheel.

L L' are two semicircular straps placed in a groove, o , in the circumference of the loose ring G'. The straps L L' are hinged or bolted together at g , and form a friction-brake for the loose ring G'. The strap L is provided with an arm or extension, h , which at i engages upon a stationary pivot. The strap L' is pivotally secured at k to one arm of the bell-crank lever M, which is pivoted at l to the extension h of the strap L. The other end 65 of the bell-crank lever M is pivotally secured at m to a link or rod, N, which connects either directly or indirectly through a system of levers with the reversing-lever N'.

In practice, with the parts arranged as shown in Figs. 1 and 2, the necessary motion of the valve is obtained in the well-known manner by the revolutions of the two-part crank-wheel G G', which act practically as one wheel if the power of the little coil-spring d is sufficient (as it must be for the successful operation of the device) to keep the dog J engaged into either of the two recesses $f f'$, against the frictional resistance of the valve and its operating parts.

To reverse the motion of the engine-crank, the operator takes hold of the reversing-lever and by a short quick pull tightens for an instant the friction-brake L L' upon the loose ring G' sufficiently to force the dog J from its engagement with the recess f or f' , as the case may be, thereby arresting the valve motion; but as the fast portion of the crank keeps on revolving by the action of the fly-wheel the dog J will soon find a new engagement into 90 the other one of the two recesses $f f'$, and as this second recess is so placed in regard to the first one that the steam is reversed before the piston has completed a given travel the engine-valve is reversed and the valve-rod is again operated by the crank-wheel G G', as before. As the positions of the wrist-pin I, by which the valve-rod is operated so as to make the engine-crank turn either the direct or the reverse way, is fixed in regard to the position of the engine-crank, it is clear that the relative positions of the recesses $f f'$ in which

the dog J engages are also fixed, and the dog J must be so placed that when it engages with either one of said recesses the proper valve motion is obtained. The lug K, which is se-

5 cured to the fast portion of the crank-wheel, travels in advance of a lug, H, and is of proper size and shape to be in contact with the latter whenever the dog J is in engagement with one of the recesses f f'. Whenever the en-
10 gine is reversed, it makes contact with the op-
posite side of a lug-pin, and as it cannot travel past the same it is clear that by its interfe-
rence it makes the reversing device always positive in its action.

15 If the operator, instead of giving a short jerky pull upon the reversing-lever, as is nec-
essary so as to release the loose ring in time to follow the reversing action, keeps the brake tightened, it is clear that the engine will, after
20 reversal, come to a dead stop, owing to the inactivity of the valve and the destruction of the momentum of the fly-wheel by the pre-
ceding reversal.

25 To prevent the dog J from turning in its socket, its head is squared, and the recess in which it enters when it is depressed is of cor-
responding cross-section.

30 I am aware that my device may be variously modified as regards the particular construc-
tion of some of the parts—for instance, the construction of the friction-brake upon the loose ring G', which may be of any other known construction suitable for the purpose. The construction of the dog J is also imma-
35 rial as long as it performs the function re-
quired—viz., to hold the loose ring in safe engagement with the fast portion of the crank, against the resistance of the operating parts of the valve, but release its engagement by a proportionately larger increase in friction.

40 What I claim as my invention is—

1. In a reversing-gear, a crank-wheel for actuating the valve, consisting of two concentric parts, the inner part being fast upon the 45 crank-shaft of the engine, while the outer part, which carries the wrist-pin for the valve-rod, forms a loose ring around it, which is kept in

engagement therewith, against the frictional resistance of the valve motion, by a spring-dog, substantially as and for the purpose de- 50 scribed.

2. In a reversing-gear, the actuating crank-wheel of the engine-valve made in two con-
centric parts, the inner part being fast upon the engine-shaft, while the outer part, to which the valve-rod is secured, forms a loose ring around it, which is kept in engagement there-
55 with, against the frictional resistance of the valve motion, by a spring-dog secured in the fast part and adapted to engage in either one 60 of the recesses in the loose ring, in combina-
tion with a friction-brake actuated by a hand-
lever and operating upon the loose ring of the crank-wheel, substantially as and for the pur-
poses described. 65

3. In a reversing-gear, the loose ring G', carrying the crank-pin of the engine-valve rod, and forming the outer concentric part of a two-part crank-wheel, the inner portion, G, of which is fast upon the engine-shaft, the 70 spring-dog J, secured to the latter and adapted to make a breakable connection between the two, the two recesses f f', the lug H and lug K, all combined and operating substantially as described.

4. A reversing-gear consisting of the two-
part crank-wheel G G', arranged and oper-
ating substantially as described, in combina-
tion with the friction-straps L L' and bell-crank
lever M, substantially as and for the purposes 80 described.

5. In a reversing-gear, the combination of the fast part G of the crank, provided with the flange a, the concentric ring G', sleeved loosely upon the part G, the washers b, secured to the 85 part G, the spring-dog J, recesses f f', lug H, lug K, and hand-brake device L L', for the loose ring G', all combined and operating sub-
stantially as described.

HARY H. HUDSON.
